UNITED STATES PATENT OFFICE.

BERTHOLD HUBER, OF TAUNTON, MASSACHUSETTS, ASSIGNOR TO THE
HUBER PRINTING PRESS COMPANY, OF SAME PLACE.

PRINTING-MACHINE.

SPECIFICATION forming part of Letters Patent No. 350,056, dated September 28, 1886.

Application filed September 29, 1884. Serial No. 144,220. (No model.)

To all whom it may concern:

Be it known that I, BERTHOLD HUBER, a citizen of the United States, residing at Taunton, in the county of Bristol and State of Massachusetts, have invented a new and useful 5 Printing-Machine, of which the following is a specification.

The object of my present invention is the production of a printing-press especially adapted for printing from sheet metal or from stereotype, electrotype, and zincographic plates.

My invention relates to a printing-press in which the impressions are given by the employment of two cylinders, upon one of which 15 is secured the form, the other being fitted with grippers in the usual manner.

It also relates to that class of presses in which water and ink are used alternately in the process of printing. In all such former constructions that part of the type-cylinder not used for the form was employed as an inking surface or table, onto which the ink was deposited from the fountain, and from which it was delivered onto the form-rollers. The inking 20 surface or table of presses heretofore employed being "type-high," or in the same circumferential line with the type, it was necessary to lift the water-rollers away from the form-cylinder at every revolution of the latter, and therefore it was impossible to drive the water-rollers by gears at the same positive speed as 25 that of the surface-speed of the cylinder.

The object of my invention is to drive the water-rollers as well as the ink-rollers by the same means, and to give both sets of rollers a positive surface-speed.

In this my invention the surface of the form-cylinder other than that occupied by the form is disposed below that portion occupied by said 30 form, while the water-rollers, having a surface-speed equal to that of the form-cylinder, are provided with positive gear mechanism, and are arranged in the circumferential line or "printing-line" of that portion of the form-cylinder occupied by the form, so that in the 35 revolution of the form-cylinder the said water-rollers travel over the surface of the form placed on said cylinder, while they do not touch the depressed surface of said form-cylinder. Furthermore, the ink-rollers are in

fixed relation with the form-cylinder, and by reason of the depressed portion, said "cylinder" comes in contact only with the form placed on the raised or normally high portion of said cylinder. By this arrangement the 55 water and ink rollers in the revolution of the form-cylinder alternately pass over the face of the form or plate placed on the normally high portion of said cylinder, but do not touch any portion of said cylinder, as is done in the common form of printing-presses, wherein a portion of the surface of the cylinder serves as an inking-table. Furthermore, the inking apparatus and the cylinder have their driving mechanism connected to and operated by a common 60 shaft, which is in constant engagement with the driving mechanism for the ink apparatus, while it has merely a clutch-connection with the mechanism for the cylinders. The object to be attained by this construction is to permit the inking apparatus to be driven independently of the cylinders, so as to enable an operator to "ink up" the ink apparatus without inking the form—an operation very essential 65 to the class of presses to which my invention belongs. Furthermore, the inking apparatus is located above the form-cylinder, so as to permit an operator to stand at the back of said cylinder to adjust the zinc plate thereon, or to remove said plate therefrom and substitute another when desired, while the water-rollers are placed beneath the form-cylinder.

The invention consists in certain novel combinations and arrangements, as hereinafter particularly set forth and claimed.

Figure 1 is a vertical section of a machine embodying my invention. Fig. 2 is a vertical cross-section on the line $x-x$, Fig. 1. Fig. 3 is a plan view of the cylinders and principal gears, the frame-work being omitted. Fig. 4 90 is a detail to be referred to. Fig. 5 shows details of the clutch mechanism on the driving-shaft, such clutch mechanism being of common construction.

The two side frames, $A' A''$, and the foundation B constitute the frame-work.

C' is the form-cylinder, onto the high part c' of which is fastened the zinc plate, which is bent at a right angle on the forward end and held in place by the nippers c'' , the tail end 100

being drawn and fastened by a number of clamps, c^3 . The opposite side, c^4 , of the cylinder C' is cut below the printing-line, so that in its rotation it will not come in contact with either the form-rollers or water-rollers.

C^2 is the impression-cylinder, and is fitted with grippers c^6 in the usual manner.

In the accompanying drawings the impression and type cylinders are of the same diameter, which, however, is not essential, as their proportions might be two to one.

C^3 is the delivery-cylinder, and is fitted with grippers c^7 .

D is the fly, and E the feed-board.

F' is the driving-shaft, journaled in the two frames $A' A^2$.

F^2 represents a tight and loose pulley on the shaft F' outside of the frame A^2 . Inside, and nearest the frame A^2 , is a pinion, G^4 , fitting loosely on the shaft F' , but capable of being fastened firmly to said shaft by the clutch F^3 . By sliding the pinion G^4 toward the frame A^2 it is released from the clutch F^3 , and the shaft F' is allowed to revolve without imparting motion to the pinion G^4 . The pinion G^4 engages the pinion G' , which is secured to the cylinder C' by screw-bolts 2, passing through slots c^5 in the gear G' , to allow the relative position of the gear G' and the cylinder C' to be changed,

so as to bring the head-line of the form in its proper position on the paper. The gear G' engages the gear G^2 , which is fastened to the cylinder C^2 , and this latter gear, G^2 , engages and drives the delivery cylinder-gear G^3 , which is fastened to the delivery-cylinder C^3 . It will therefore be seen if the pinion G^4 is thrown into the clutch F^3 , then the rotation of the shaft F' will drive the train of gears G', G^2 , and G^3 with their attached cylinders C', C^2 , and C^3 . If the pinion G^4 is thrown out of the clutch F^3 , then the rotation of the shaft F' will not be transmitted to the said train of gears and their attached cylinders.

Fastened on the driving shaft F' , near its opposite end, (see Fig. 3,) is another pinion, H' , which meshes into the gear H^2 , loose on a journal of the cylinder-shaft, and free to rotate thereon without moving the cylinder C' . The gear H^2 meshes in turn into the three intermediate gears, H^3 , (shown in dotted lines in Fig. 1, and in section in Fig. 4,) said gears H^3 engaging the gear h^4 on and driving the distributor or vibrator rollers H^4 for the ink, and also the water-distribution roller o^2 in like manner. The gear H^2 also drives the intermediate gear, H^5 , which meshes into the gear H^6 , (see Fig. 2,) which is fastened to the ink-drum I , upon which rest four small rollers, k' . The ink is transmitted from the ink-fountain L' to the ink-drum I by the roller k' , which oscillates between the said ink-fountain and ink-drum around the shaft I^2 in usual manner. From the ink-drum I the ink is conducted to the form-rollers by the intermediate rollers, k^2 , and the distributor or vibrator rollers H^4 , which latter, as stated before, receive a posi-

tive motion from the cylinder C' through two of the intermediate gears, H^3 .

On the outside of the frame A' and fastened to the shaft of the drum I is a pinion, p' , (see Fig. 2,) which drives the gear p^2 , fastened to the shaft p^3 . The pinion p' and the gear p^2 are so proportioned that the shaft p^3 makes one turn to every revolution of the cylinder C' , and is used for the usual and necessary mechanism (not shown) to oscillate the rollers k^2 between the ink-fountain and ink-drum and vibrate the distributor or vibrator rollers. The water is transmitted from the water-fountain roll o to the distributor-roll o^2 by the roll o' , which oscillates between the fountain-roll o and the distributor-roll o^2 around the shaft o^4 . The water-distributor roll o^2 and the water form-rollers o^3 are journaled in the arms o^6 , the upper ends of which are hinged on the studs o^7 , while their lower ends rest on the eccentric-shaft o^5 . The position of the arms o^6 , as shown in the drawings, will keep the water-rollers close to the cylinder, and in what might be called the "working position," while upon reversing the eccentric-shaft o^5 the arms o^6 will be lowered to throw the gear H^3 , which engages the distributor-roll o^2 , out of gear with the gear H^2 on form-cylinder C' , and thus make it convenient to remove the water form-rollers from contact with the form-cylinder. By bringing the cylinder C' into the position where the type-surface c' will be located between the water-rollers o^3 and the first form-roller at the back side of the machine and then sliding the pinion G^4 out of the clutch F^3 on the shaft F' the machine is then in the most convenient position for inking up.

Upon putting the machine in motion the cylinders $C' C^2 C^3$ will remain stationary, but the inking apparatus will be in motion, and the distribution of ink and water may be adjusted and regulated ready for printing. Did the form-rollers depend upon an inking surface or table on the cylinder C' , then the motion of the cylinder C' would be necessary during the operation of inking up, and the impression-cylinder C^2 would have to be separated from the form-cylinder C' . On the other hand, by using instead of an inking surface or table in the form-cylinder a separate ink-drum, I , I obtain the advantage of running the ink and water apparatus independently of the cylinders, and also the advantage of driving the water-rollers in a positive manner, thereby securing a more even damping.

I claim—

1. In a rotary printing-press, the form-cylinder having a form-surface and a depressed or cut-away surface below the level of said form-surface, an ink-drum, and form-rollers, combined with a main driving-shaft for rotating said cylinder and drum, and thereby the said rollers, substantially as described.

2. The combination, with the form-cylinder having a form-surface and a cut-away surface below the level of the form-surface, as

specified, and provided with a fixed gear, and a driving-shaft provided with a fast gear, a loose gear, and clutch, of an ink-drum and the ink and water distributer rollers and gear mechanism connecting the drum and rollers with the fixed gear on the driving-shaft, substantially as and for the purpose set forth.

3. The combination, with the form-cylinder having a form-surface and a cut-away surface below the level of the form-surface, as specified, and provided with a fixed gear, and a driving-shaft provided with a fast gear, a loose gear, and a clutch to engage the loose gear, of an ink-drum, ink-distributer rollers, and gear mechanism, substantially as described, connecting the ink drum and rollers with the fast gear on the driving-shaft, and the form-inking rollers retained in frictional contact with the distributer-rollers, substantially as described.

4. The combination, with the form-cylinder having a form-surface and a cut-away surface below the level of said form surface, as specified, the impression-cylinder at one side of the form-cylinder, and the water-rollers below and adjacent to the form-cylinder, of the ink-drum arranged above the form-cylinder, an ink-distributer and form-rollers intermediate of the drum and form-cylinder, and a main driving-shaft and gearing connecting said shaft and the cylinder, drum, and rollers to positively actuate them, substantially as and for the purpose set forth.

5. In a rotary printing-machine, the shaft F', with two pinions, one, H', firmly secured to said shaft, and the other, G', provided with a clutch, F³, of the cylinders C' C² C³, with their respective gears G' G² G³, forming a train

and driven by the pinion G⁴ when engaged by the clutch F³, combined with the gear H², loose on the shaft of the cylinder C' and driven by the pinion H', and to drive in turn the inking and water apparatus, substantially as set forth.

6. The water-distributer roller o² and the water form-rollers o³ in frictional contact with the said water-distributer roller, swinging arms o⁶, in which said water-distributer and form rollers are arranged, and means, substantially as described, to raise and lower them with respect to the form-cylinder, combined with the form-cylinder having a form-surface and a cut-away or depressed surface, substantially as described.

7. The combination, with the form-cylinder having the loose gear H², of the swinging arms o⁶, provided with the water-distributer roll o², the water form-rollers o³, and the gear H³, engaging the gear H² and a gear on the distributer-roll o², and the cam-shaft o⁵, all arranged to operate substantially as described.

8. The combination, with the form-cylinder, ink-drum, form-rollers, and gearing, substantially as set forth, connecting the said cylinder, drum, and rollers, of a main driving-shaft provided with a clutch-gear for actuating the said cylinder and adapted to be thrown out of gear with said cylinder and by the same motion thrown into gear with the form-inking rollers, substantially as described.
